S. P. BRICKER,
WEATHER STRIP.
APPLICATION FILED FEB. 15, 1909.

1,143,033.

Patented June 15, 1915.

UNITED STATES PATENT OFFICE.

SAMUEL P. BRICKER, OF PITTSBURGH, PENNSYLVANIA, ASSIGNOR TO NATIONAL METAL WEATHER STRIP COMPANY, OF PITTSBURGH, PENNSYLVANIA, A CORPORATION OF PENNSYLVANIA.

WEATHER-STRIP.

1,143,033.

Specification of Letters Patent. Patented June 15, 1915.

Application filed February 15, 1909. Serial No. 478,067.

To all whom it may concern:

Be it known that I, SAMUEL P. BRICKER, a citizen of the United States, residing at Pittsburgh, North Side, in the county of 5 Allegheny and State of Pennsylvania, have invented certain new and useful Improvements in Weather-Strips, of which the following is a specification, reference being had therein to the accompanying drawing.

10 My invention refers to improvements in metallic weather strips and relates particularly to frame member strips adapted to be used with the parting bead of the window frame in combination with co-acting strips 15 mounted on the side members of the sash and top rail of the upper sash, or with a grooved sash.

Generally stated, the strips are made of thin sheet metal, preferably zinc or any 20 other suitable non-corrosive metal, bent to provide attaching portions for securing to the parting bead of a window frame, and having projecting ribs or flanges interfitting with grooved sash elements, or a groove or 25 grooves co-acting with an inter-engaging rib, in the manner generally similar to this class of weather strips, to effectually close the opening between the sash and the frame against the passage of the elements, to make 30 a weather-tight fit.

The particular object in the present invention is to provide a frame member which may be mounted upon the parting bead of the frame by portions embracing its sides, 35 between the opposing sides or faces of the upper and lower sash respectively, adapted as thus mounted upon the parting bead to co-act with the sash member or members.

Heretofore in attaching the frame member of tongue and groove strips it has been customary to set it between the beads in the runway of the sash, requiring removal of the sash and of the parting bead and of the outer bead. My improved frame member is 45 constructed and adapted to be applied to the parting bead without the removal of the sash or the requirement of practically any cutting of the wood.

50 In the drawings illustrating the invention: Figure 1 illustrates in perspective the construction of one form of the frame member. Figs. 2 and 3 are similar views of two forms of co-acting sash members. Figs. 4,

4^a, and 5 are horizontal sectional views through portions of the frame and sash, 55 showing the frame and sash members in operative position. Fig. 6 is a sectional view showing a modified construction of sash member. Figs. 7, 8, 8^a, 9 and 10 are views similar to Figs. 4, 5 and 6, showing further 60 modified constructions. Figs. 11 and 12 illustrate modifications of the frame member shown in Fig. 1. Figs. 13 and 14 are sectional views similar to Fig. 4 showing further modified constructions. Fig. 15 is a 65 perspective view similar to Fig. 1 but with a single tongue. Figs. 16, 17, 18 and 19 show sectional views of further modified constructions.

Generally stated, the frame member A is 70 formed of a longitudinal blank of thin sheet metal bent to provide parallel sides 2, 2, arranged to embrace the sides of the parting bead 3. Said sides, in the form illustrated in Figs. 1, 4, 11, 12, 14 and 15 extend 75 outwardly in the same parallel plane and are doubled upon themselves at each side to provide the double-sided ribs 4, 4, the metal forming the inner side of each rib extending backwardly as shown, part way for the full 80 depth of the rib, and then across at right angles providing the intermediate connecting web or partition 5, which constitutes the front face of the strip, adapted to bear against the front of the parting bead 3, as 85 clearly shown in Fig. 4. The frame member as thus made, is preferably of dimensions adapted to fit upon the standard parting bead and of a width of $\frac{3}{8}$, $\frac{1}{2}$, or $\frac{5}{8}$ of an inch as desired, and when set thereon will tightly 90 embrace the parting bead by its sides. The inner edges of sides 2 preferably extend inwardly beyond the face of the runway to the full depth of the parting bead, for which purpose narrow grooves may be scribed in 95 the wood at each side of the bases of the parting bead, as indicated at 6, 6, Fig. 4.

The strip may be secured to the parting bead by nails or screws driven inwardly through web 5 as indicated, or the sides 2 100 may be similarly secured to the sides of the parting bead, as preferred.

In Fig. 4^a the frame strip embraces the side or bead 3 by one side 2' only, the front web 5' extending across its front and then 105 outwardly in single thickness, providing the

sealing rib 4'. Such rib inter-engages with any suitable sash member strip B, as of the form shown in Fig. 3, so that when assembled for both sashes, in reversed position, the entire parting bead will be covered.

In Fig. 11 the edges of the sides 2 are bent inwardly to provide terminal flanges 7 which may embrace the back edges of the parting bead, in which construction it is necessary to first remove the parting bead to apply the strip thereto, replacing the parting bead with the strip attached. Likewise, the rear terminal edges of sides 2 may be bent outwardly at right angles to provide securing flanges 8 as indicated in Fig. 12, by which the strip may be secured by nails or screws driven into the face of the runway. With either construction the entire parting bead will be covered by a metallic sheathing forming the body portion of the frame member strip and having the sealing ribs 4.

The sash frames 14 are provided with any suitable co-acting sliding members B, as of the different forms shown.

In Fig. 2 the sash member is formed from a similar strip of metal to provide an attaching flange or base 9, doubled back upon itself as indicated at 10, of double thickness and then reversed and extended outwardly by its terminal edge portion 11, providing the intervening space 12 adapted to embrace the rib 4 and make sliding engagement therewith, as will be readily understood. In Figs. 3 and 4 the sash member is of simpler form, composed of the base 9' and the terminal backwardly bent edge portion 11' providing the intervening space 12' for embracing the rib 4.

In Fig. 5 the construction of the frame member is generally similar to that already described except that the projecting sealing ribs 4 are located somewhat more closely together and set inwardly from the sides 2 by off-set corners 13, said figure showing the sash 14 provided with the form of sash member shown in Fig. 2.

Fig. 6 illustrates another form of sash member for operation with the form of frame member shown in Fig. 5, in which the base 9'a extends in the opposite direction, whereby it is concealed beyond the parting bead.

In Fig. 7 the frame member is similar to the construction shown in Fig. 1, but having additional ribs, the outer sealing ribs 4'a extending in the same plane as the sides 2'a while the intervening additional ribs 4'b are provided by doubling the metal upon itself outwardly in the same manner as in forming the ribs 4, whereby four of such ribs are provided, arranged transversely across the face of the strip. By this construction I provide pairs of ribs at each side of the center, with which ribs co-act correspondingly formed sash members having the double receiving

grooves formed by doubling the metal upon itself, in the same manner generally as is shown in my prior Patent No. 712761, the sash member having a securing flange 9'b as clearly shown.

In Fig. 8 the frame member is provided with the sides 2'e adapted to embrace the sides of the parting bead 3, the front web 5'e making a right angled connection therewith at each corner, the sides 2'e being reversed upon themselves and bent outwardly by their terminals 11'e, providing an intervening space for the reception of the projecting rib of a suitable sash member. Such sash member may be merely a single thickness strip as indicated in Fig. 8 or may be of the form shown in Fig. 9 having the double-sided rib 10'd offset from its base 9'd, by which it is secured to the sash 14.

In Fig. 8'a the same construction of frame member is shown, at one side only of the parting bead, adapted to interengage with any suitable sash member. In this form the other side merely operates to cover the bead, and may be made in lengths for each sash, upper and lower, and reversed as to front and back.

The sash member may also be made in any other suitable form as indicated in Fig. 10, in which a single thickness rib 10'e is provided by doubling the metal upon itself to provide an intervening space 12'e to receive the terminal 11'e of the frame member of Fig. 8, the sash member having a right angle flange or base 9'e, by which it is secured to the sash 14.

In Fig. 13 the frame member is similar to that of Fig. 8, but is provided with an additional re-doubled side 15 providing intervening space 16 adapted to receive a sealing rib 11'f of the sash member, secured to the sash by its flange or base 9'f.

In Fig. 14 I show the sash member as of the same general construction as that of Fig. 1, except that the front 5'g is outwardly bowed to fit upon the oval or rounded front of the parting bead 3. It will be understood that the front 5'g may be of any desired cross section, as semi-circular or otherwise, to conform to and make snug engagement with the cross sectional construction of the parting bead. In said figure the sash member is similar to that shown in Fig. 10 but extending outwardly sufficiently far to embrace the rib 4'g by its reversed side 10'g, providing the intervening space for the rib as clearly shown.

Fig. 15 shows the frame member A constructed like Fig. 1 but having the sealing rib 4'h at one side only, extending in the same plane as one of the sides 2'h, with the front connecting web 5'h. This form of construction is of advantage and economy where it is desired to provide the sealing rib for one sash only or for the lower and upper sash 130

respectively at opposite sides of the parting bead. Thus the full height of the parting bead at each side of the frame may be equipped with two sections of the single rib 5 strip, reversed to each other to present the rib for each sash at the proper side of the bead. This form may also be used to advantage for the top of the frame, and also, if desired, for the sill.

10 It will be understood that other constructions of the parting-bead-embracing frame member strip may be designed having the single double-thickness rib located to suit various forms of co-acting frame members, 15 or to enter either a bare or lined groove in the frame.

Thus in Fig. 16 the frame member is provided with a laterally arranged rib 4^l extending at one or both sides from the strip 20 A at right angles to the sides 2^l, in the same plane as the front web 5^l, and into a receiving groove 12^l in the adjacent face of the sash 14.

In Fig. 17 the rib 4^l of the frame member 25 extends laterally from an intermediate position on the side 2^l and is embraced by the sash member B secured to the sash as shown and of a form similar to the strip shown in my prior Patent No. 712761 and having a 30 suitable attaching base. This form of sash strip is of advantage in providing cushioning resilience for lateral movement, shrinkage or expansion of the sash, without impairing the sealing action.

35 In Fig. 18 the frame member strip A is also similar, having the lateral sealing rib 4^k entering a groove fitted with a suitable cushioning substance 11^k as rubber or felt, the operation being similar to that of 40 Fig. 17.

In Fig. 19 the sealing rib 4^l of the frame strip extends laterally from a part of the front web 5^l about midway of its width, and is embraced between the sliding sides of the 45 sash member B, similar in construction to

the strip shown in my prior Patent No. 849366.

An especial advantage of the frame member is that it completely covers and protects the parting bead, and the entire equipment 50 is of small compact construction, easily put on or off, without necessitating removal of the parts of the window; it is simple, economical, efficient and durable, and greatly contributes to the appearance and easy operation of opening and closing the sash.

The invention may be changed or varied in construction or design by the skilled mechanician, but all such changes are to be considered as within the scope of the following 60 claims.

What I claim is:—

1. The combination with the parting bead of a window frame, of a sheet metal strip formed to embrace the bead and having a 65 rib extending directly from one of the bead-embracing portions, a co-acting sash, and a sash member strip secured thereto and embracing the parting bead rib, substantially as set forth.

70 2. The combination with the parting bead of the runway of a window frame extending outwardly from the face of the runway, of a sheet metal weather strip having a side and front permanently rigidly embracing the 75 parting bead, the metal of one of said bead-embracing parts being doubled upon itself and providing a sealing rib extending directly from one of the bead-embracing portions in a plane parallel with one of the 80 faces of the parting bead, and a co-acting sash having a portion embracing said rib, substantially as set forth.

In testimony whereof I affix my signature in presence of two witnesses.

SAMUEL P. BRICKER.
